UNITED STATES PATENT OFFICE.

GEORGE S. LOCKWOOD, OF SAGINAW, MICHIGAN.

COMBINED LANTERN OR LAMP POST FOR USE ON SMALL WATER-CRAFT.

No. 853,310.

Specification of Letters Patent.

Patented May 14, 1907.

Application filed September 19, 1906. Serial No. 335,231.

To all whom it may concern:

Be it known that I, GEORGE S. LOCKWOOD, a citizen of the United States, residing at Saginaw, in the county of Saginaw and State of Michigan, have invented a new and useful Manufacture Consisting of a Combined Lantern or Lamp Post for Use on Small Water-Craft.

My invention consists of a locking device for holding in place, on a post, a lantern or lamp and may be used with any lantern having a bail or arched movable handle, or with any lamp having a socket for support, such as the ordinary oil or acetylene bicycle lamp or other lamps having a similar device or socket for support; and the objects of my invention are to prevent the loss of a lamp or lantern, so supported on small water craft, by theft, capsizing or other possible cause and to provide a rigid and convenient support for such lamp or lantern. I attain these objects by the device illustrated in the accompanying drawing, in which—

Figure 1 is a rear view of the lamp post locked in position; Fig. 2 is a side view of the same; Fig. 3 is a plan view of base plate and socket *e*; Fig. 4 is a view in perspective of the lantern post *a*; Fig. 5 is a view in perspective of the locking bar *g*; similar letters refer to similar parts throughout the several views.

a is the post or lamp support provided at its upper end *r* with a slotted opening *h* adapted to receive the hooked end *m* of the locking bar *g*.

k is a cylindrical enlargement of the post *a* just below the slotted hole *h* of a suitable diameter to receive a round socket secured to the frame of a post lamp or lantern; the projecting lugs *l* at the lower end of cylinder *k* form a stop for the same. The horizontal top of the cylinder *k* with the vertical part of *r* of post *a* also form a shoulder for supporting the bail of a lantern.

The foot of post *a* is provided with a shoe *o* adapted to slide into a socket in base plate *e*. The shoe *o* is formed at a suitable angle to post *a* to allow same to incline enough from the vertical to allow the frame of a lantern to swing free from same when the bail of

a lantern is supported and over the shoulder formed by the cylinder *k*. The base plate *e* is provided with a suitable socket for receiving the shoe *o* of post *a*, also lateral flange *b* provided with openings for bolts *c* for securing same to the deck *p* of a vessel. 55

d is a staple or **U** bolt passing through the base plate *e* also through the deck *p* and plate *f* on the under side of deck, to which the eye *n* of locking bar *g* is secured by means of an ordinary padlock *j*. 60

In operation the post *a* is slid into the socket of base plate *e*, the bail of a lantern is hung over the shoulder formed by the cylinder *k*; then the end *m* of the locking bar *g* is 65 inserted into the slotted opening *h* of post *a*, then by turning the bar *g* down one quarter turn it will bring the eye *n* of same in line with the top of staple bolt *d*; the two may now be connected and locked together by 70 means of a lock as for instance an ordinary pad lock as shown in the drawings; while the locking bar *g* is secured to the staple *d* the lantern cannot be removed from the post *a* and post *a* cannot be removed from the base 75 plate.

I claim:

1. A lockable lamp holder, comprising a fixed base plate, an upright post detachably connected to said base plate, a lamp support 80 near the upper end of said post and a slotted opening above said support, a **U** bolt secured to said base plate; a connecting bar having a hooked end adapted to securely hook into said slotted opening and the other end terminating in an eye; a shackle connecting said eye and **U** bolt and any means for locking said shackle for the purpose set forth. 85

2. In a lockable lantern holder the combination with an upright post detachably connected to a rigid base, of a connecting bar removably connected to the top of said post and extending diagonally downward to the said base and terminating in an eye; a **U** bolt secured to the said base and a shackle 90 for securing said **U** bolt to the eye of the connecting bar, and means for locking said shackle for the purpose of preventing the removal of said post from the base. 95

3. In a lockable lantern holder the combi- 100

nation with an upright post detachably connected to a fixed base of a U bolt secured to said base; a lantern support near the upper end of said post, a connecting bar removably secured to said post above said lantern support and extending diagonally down and connecting with said U bolt by means of a pad-

lock substantially as shown and for the purpose specified.

GEORGE S. LOCKWOOD.
